UNITED STATES PATENT OFFICE.

EDMUND DAWSON ROGERS, OF CHURCH END, FINCHLEY, COUNTY OF MIDDLESEX, ENGLAND, ASSIGNOR TO PAUL WILCOX, OF NEW YORK, N. Y.

MEANS FOR SECURING STEREOTYPE-PLATES WHICH ARE CAST SEPARATELY FROM THEIR BEDS.

SPECIFICATION forming part of Letters Patent No. 406,371, dated July 2, 1889.

Application filed September 17, 1887. Serial No. 250,007. (No model.) Patented in England June 4, 1880, No. 2,275.

To all whom it may concern:

Be it known that I, EDMUND DAWSON ROGERS, a subject of the Queen of Great Britain and Ireland, residing at Church End, Finchley, in the county of Middlesex, Kingdom of Great Britain and Ireland, have invented Improvements in the Means for Securing Stereotype-Plates which are Cast Separately from their Beds, (for which I have obtained a patent in Great Britain, No. 2,275, bearing date June 4, 1880,) of which the following is a specification.

The object of this invention is to make stereotype-plates and their beds in such manner that the plates can be placed and secured on the beds without necessitating an inconvenient disturbance of adjoining pages or columns.

According to my invention the plates are placed on the beds by downward motion, and are locked up by the ordinary column-rules, as shown, or other furniture of sufficient height.

In the annexed drawings, Figure 1 is a cross-section, and Fig. 2 a plan, partly in section, of a plate and bed.

a is the plate. It is formed with vertical flanges *b b* along its edges.

c is the bed. It is made with corresponding recesses *d d*, into which said flanges *b b* fit. Thus by placing the plate *a* by a downward

movement upon the bed *c* the plate and bed will be locked up by the ordinary column-rules or other furniture of sufficient height.

What I claim is—

1. A stereotype-plate provided with straight vertical flanges along its edges and at right angles thereto, in combination with a bed provided with correspondingly-shaped recesses to receive said flanges, and means for holding said plate in position, substantially as described. 35

2. A type-plate having along its edges and at right angles thereto and integral therewith rigid non-flexible vertical side flanges *b*, in combination with a block provided with vertical sides against which said flanges may rest, and whereby the said flanges are adapted to fit loosely over the said vertical sides and permit the ready removal of the plate by lifting it vertically from the block, substantially as set forth. 45

In testimony whereof I have signed my name to this specification in the presence of two subscribing witnesses.

EDMUND DAWSON ROGERS.
